(57) **CLAIM**

I claim the ornamental design for the fence post, as shown.

DESCRIPTION

FIG. 1 is a front perspective of a fence post showing my new design;

FIG. 2 is an end elevation of the fence post of FIG. 1 and the other end being a mirror image;

FIG. 3 is a side elevation of the fence post of FIG. 1, the other side being a mirror image;

FIG. 4 is a top plan of the fence post of FIG. 1, and,

FIG. 5 is a bottom plan of the fence post of FIG. 1.
